COMBINED KNOB AND ESCUTCHEON FOR A COMBINATION LOCK

Robert K. Unter, Roscoe, Ill., assignor to National Lock Co., Rockford, Ill., a corporation of Delaware

Filed May 27, 1964, Ser. No. 80,180

Term of patent 14 years

(Cl. D50—7)

FIG. 1 is a front perspective view of a combined knob and escutcheon for a combination lock embodying my new design;

FIG. 2 is a front elevational view thereof;

FIG. 3 is a side elevational view thereof; and

FIG. 4 is a top plan view thereof.

The essential features of the combined knob and escutcheon for a combination lock reside in the portions shown in full lines.

I claim:

The ornamental design for a combined knob and escutcheon for a combination lock, substantially as shown and described.
